UNITED STATES PATENT OFFICE.

GEORGE F. LYMAN, OF NORFOLK, VIRGINIA.

SASH-HOLDING DEVICE.

SPECIFICATION forming part of Letters Patent No. 727,815, dated May 12, 1903.

Application filed March 7, 1902. Serial No. 97,104. (No model.)

To all whom it may concern:

Be it known that I, GEORGE F. LYMAN, a citizen of the United States, residing at Norfolk, in the county of Norfolk and State of Virginia, have invented certain new and useful Improvements in Sash-Holding Devices, of which the following is a specification.

My present invention pertains to improvements in sash-holding devices, the construction and advantages of which will be herein-after set forth, reference being had to the annexed drawings, wherein—

Figure 1 is a face view of a window-sash looking from the inside outward, parts of the window framing and sash being broken away; Fig. 2, a view showing portions of the window-casing in section and the side or edge of the sash with the attached clamp or antirattler in position therein; Fig. 3, a transverse sectional view on the line 3 3 of Fig. 2; Fig. 4, a perspective view of the edge of the sash; and Fig. 5 a perspective view of a portion of the clamping device.

The object of the invention is to provide a simple spring-pressed device capable of ready application to the edge of a window-sash and which when in position will act against the bead-strip or other portion of the window-frame to force the sash bodily up against the opposite retaining member, thereby holding the sash closely to place and accomplishing the double purpose of preventing the sash from rattling and practically closing off the passage of air around the sash.

I am aware that it is not new to provide window-sash with devices of this general nature. The present construction, however, is simple and advantageous and in practical use has been found highly efficient.

In the drawings, A denotes a window-sash, B the dividing bead-strip, and C the inner bead or retaining-strip. In the edge of the sash, and preferably at its mid-length if the sash be a light one, I bore two openings D and E, which openings are connected by a space or channel F. A recess of this contour is formed in each of the upright members of the sash in the outer edge thereof, as best indicated in Fig. 1, the sash being broken away upon the left of said figure to indicate the position of the antirattler, while the inner bead-strip C is simply broken away upon the right,

showing that the opening formed in the edge of the sash does not extend through to the inner face thereof. The antirattler comprises a spring-arm G, carrying at its upper end a roller H, said roller being formed with a deep groove or channel extending around the periphery thereof, which leaves an axle I, about which the upper end of the spring-arm G is coiled. The lower end of the member or arm G is bent rearwardly at right angles to the main body thereof, forming an arm J. The end of the wire of which the body is constructed is then bent at right angles to the arm J, forming a third short arm or projection K. The arm J stands at right angles to the axis of the roller H, while the arm K lies in a plane parallel with the axis of said roller. To secure the spring-arm in its proper position, I employ a button or disk L, having a groove or channel M formed in the rear or under face thereof, with a second groove or channel N formed in the edge of said disk. These grooves or channels M and N are adapted to receive the arms J and K, respectively, when the parts are positioned, as best shown in Figs. 2 and 4. The disk is also provided with two openings O, extending therethrough, adapted to receive screws or similar fastening means by which the device as a whole is secured in place. Said disk L fits within the lower opening or recess E and may be rotated to bring the spring-arm G to its proper position before the screws are inserted to hold the device in place.

Before the sash is put in position the arm G will stand in alinement with the outer edge of the sash, with the roller projecting beyond the face thereof. When, however, the sash is in position, as indicated in Figs. 2 and 3, the roller will be pressed back into the upper recess D and the spring-arm put under tension. The roller H bearing against the bead-strip will force the sash inwardly against the inner bead-strip, preventing the sash from rattling and also holding it so close to place as to practically preclude the passage of any air around the sash.

With a light sash the friction or clamping action exerted by the devices upon each side thereof will hold the sash in an elevated position at any desired point. With heavy

sash it may be desirable to employ two of the devices upon each side, though in practice one has been found sufficient for the average sash.

5 Having thus described my invention, what I claim is—

1. In a device of the character described, the combination of a spring-arm having its lower end bent at substantially right angles 10 to the main body thereof; a locking device engaging said lower end; connections intermediate said arm and said locking device; and a roller carried by the free end of the spring-arm, substantially as described.

15 2. In a device of the character described, the combination of a spring-arm G provided at one end thereof with the arms J and K, said arm J extending at right angles to the main body of the arm G, and the arm K extending at right angles to the arm J and ly-

ing in a plane at substantially right angles to the longitudinal axis of the main arm G; a disk or button L having grooves or recesses therein to receive the arms J and K; and a roller carried by the free end of the arm G. 25

3. In combination with a sash having circular recesses D and E formed in the edge thereof, with a channel F connecting the same; a button or disk L mounted in said lower recess E; means for securing said button 30 in said recess; a spring-arm G; connections intermediate said arm and the disk; and a roller carried by the upper end of said arm G.

In testimony whereof I have signed my name to this specification in the presence of 35 two subscribing witnesses.

GEORGE F. LYMAN.
